UNITED STATES PATENT OFFICE.

VICTOR REGINALD DESPARD, OF CHICAGO, ILLINOIS.

ELECTRIC LAMP SOCKET.

1,171,180.

Specification of Letters Patent.

Patented Feb. 8, 1916.

Application filed May 27, 1914. Serial No. 841,203.

To all whom it may concern:

Be it known that I, VICTOR R. DESPARD, of Chicago, in the county of Cook and State of Illinois, have invented certain new and useful Improvements in Electric-Lamp Sockets, of which the following is a specification.

The object of this invention, generally stated, is to provide an improved means for securing an electric lamp socket to an electric signboard.

The invention aims to provide a socket of such construction that the operation of attaching the socket to the signboard may be performed entirely at the rear side of said board.

The features of the invention will be more fully understood from the following detailed description taken in connection with the accompanying drawings, in which—

Figure 1 is a fragmental rear side view of a signboard and a rear end view of my improved lamp socket attached to said board. Fig. 2 shows the socket as it appears from the front of the signboard. Fig. 3 is a side elevation of the socket, a portion thereof and the signboard being shown in section. Fig. 4 is an elevation at right angles to Fig. 3.

In so far as its relation to the electric lamp is concerned, the socket may be of any common or preferred construction, being herein shown as comprising the body portion 5 having therein the usual threaded metallic shell 6 and contact piece 7. The parts 6 and 7 are electrically connected to plates 8 and 9, respectively, upon the end of the body 5, said plates having the usual mounting screws 10 by which the workman may attach wires to the socket.

Adjacent to its open end the body is provided with an annular rib 11 and two diametrically opposite lugs 12. This leaves a projecting lip 13 at the end of the socket which is adapted to pass through the opening in the signboard A, the rib 11 and lugs 12 forming a continuous shoulder arranged to abut against the rear face of the signboard around the opening therein. The socket is held in this position by a pair of fingers 14 which pass through openings in the lugs 12 and through the opening in the board A and have angular or hooked ends 15 to engage the forward face of the board. These fingers are pivotally carried at their opposite ends by a pair of spring arms 16

pivoted at 17 in the lugs 12. In their preferred form, these arms are of U-shape, the ends of the U being turned in to enter the lugs 12, and the sides of the U being bowed laterally, as seen most clearly in Fig. 3, to provide the desired resiliency in the arms. The arms fit snugly alongside the body of the socket. The resiliency in the arms acts to clamp the board A firmly between the angular ends 15 of the fingers and the rib 11. Preferably the ends or hooks 15 are transversely curved to present two relatively sharp edges which bite against the board A and thus more firmly hold the socket against rotation.

When the arms 16 are swung outwardly away from the body into the position shown in Fig. 3, the fingers 14 lie at the outside of the pivot points 17, and the angular ends 15 lie alongside the body of the socket so that said angular ends may readily be withdrawn along with the lip 13 through the opening in the board A. The lugs 12 are notched as at 18 to permit the outward swinging movement of the fingers 14, and if desired the body 5 may also be notched as at 19 (Fig. 2) to receive the fingers.

When the parts are in their clamping position, as seen in Fig. 3, the fingers 14 lie at the inside of the pivot points 17 of the arms 16. The line of pull is directly along the fingers 14 from their point of attachment to the middle of the arms 16 to the angular ends 15. Therefore, the resiliency of the arms acts to hold the fingers in their operative position.

In attaching a socket to the board A, the arms 16 are first swung outward away from the body 5, the lip 13 and angular ends 15 are passed through the opening in the board A, and the arms 16 are then swung inwardly alongside the body. The socket is now firmly clamped to the board. In the inward movement of the fingers 14 they pass over the centers or pivot points 17 and the resiliency of the arms 16 then acts to snap the arms inwardly against the body. The resiliency of the arms also permits different thicknesses of boards A to be accommodated between the finger ends 15 and the rib 11. The socket is clamped firmly but yieldingly so that no breakage will occur.

With some of the sockets heretofore produced it is necessary to form an irregular or non-circular opening in the signboard to receive the socket, and the latter must be

secured in place in a definite relation to said opening. With my socket a plain circular opening is formed in the board, which cheapens the manufacture, and the socket 5 may be secured in place in any position in the opening. The relative positions of the sockets in their openings may thus be varied at will to facilitate the attachment of the electric wires. The hooks 15 will engage 10 the board A just as well in one position as in another.

It will be seen that I have provided a socket which is arranged to be mounted in place entirely from the rear side of the board. It is not necessary when working on 15 a large signboard, as is the case with some prior sockets, to have an assistant at the front of the board to insert the socket or a part thereof through the opening in the board. 20

I claim as my invention:

1. The combination, with a signboard having an opening therethrough, of a lamp socket having a lip adapted to project forwardly into said opening and having a part to abut against the rear face of the board, a member adapted to engage the front face of the board, and spring means acting on 25 said member to clamp the board between 30 said member and said part.

2. The combination, with a signboard having an opening therethrough, of a lamp socket having an annular rib adjacent to its open end, a lip adapted to project forwardly through said opening, said rib being adapted to abut against the rear face of the signboard, a pair of fingers adapted to project forwardly through said opening and engage the front face of the signboard 35 adjacent to the edge of the opening, and 40 spring means acting on said fingers to clamp the signboard between said fingers and said rib.

3. The combination, with a mounting-board, of a lamp socket abutting against one face of said board, a member having a hooked portion to engage the opposite face of the board, and spring means mounted on 45 the socket and acting on said member to 50 cause the hooked portion to grip the board and secure the socket thereto.

4. The combination, with a signboard having an opening therethrough, of a lamp socket having a portion adjacent to its open 55 end which is insertible through said opening from the rear side of the board, said socket having a shoulder arranged to abut against the rear side of the board, and spring-actuated means to pass forwardly 60 through said opening and engage the front side of the board for securing the socket in place.

5. The combination, with a board having an opening therethrough of an electrical 65 receptacle having a portion lying in said

opening, and a rib to abut against the face of the board adjacent to said opening, clamping means mounted on said receptacle at the side of the board adjacent to said rib, said clamping means having a portion 70 passing through the opening in the board and engaging the opposite face thereof and spring means connected to the receptacle at the same side of the board as that at which the rib is located, for actuating said 75 clamping means.

6. A lamp receptacle body, two fingers having hooked clamping ends and two U-shaped spring arms located at opposite sides of the body, each arm having two ends 80 which are pivoted to the body, each of said fingers being pivoted to the middle of one of said arms.

7. The combination, with a mounting-board, of an electrical receptacle adapted to 85 abut against one face of said board, a finger having a hooked end adapted to pass through an opening in the board and engage the opposite face thereof, and spring means acting on said finger to draw the 90 hooked end against said opposite face.

8. The combination, with a signboard having an opening therethrough, of a lamp socket having a lip at its open end adapted to project through said opening and having 95 a rib adapted to abut against the rear face of the signboard, means at one side of the socket adapted to engage the front face of the signboard, a spring-arm pivoted on the other side of said socket, and a finger 100 operable by said arm and having a hooked end adapted to pass through said opening and engage the forward face of said board when said arm is swung alongside the socket.

9. The combination, with a mounting-board, of an electrical receptacle adapted to 105 abut against one face of said board, clamping means having a portion adapted to pass through an opening in said board and engage the opposite face thereof to secure the receptacle to the board, and spring actuating-means pivotally attached to the receptacle and also pivoted to the clamping means.

10. The combination, with a signboard having an opening therethrough, a lamp socket having at its open end a lip adapted to project through said opening, said socket also having an annular rib adapted to abut against the rear face of the board adjacent to said opening, a pair of diametrically opposite lugs on the socket, a pair of spring-arms pivoted in said lugs, and a pair of fingers carried by said arms and having hooked ends adapted to pass through said opening along with said lip when the arms are in one position, said arms being adapted to be swung to carry said hooked ends into engagement with the front face of the board adjacent to said opening.

11. The combination, with a mounting-board, of an electrical receptacle adapted to abut against the rear face of the board, a pair of spring-arms pivoted on the receptacle and a pair of fingers pivoted to said arms and adapted to engage the front face of said board to clamp the receptacle thereto when said arms are in a certain position.

12. A lamp receptacle body, means at one side of the body for engaging a sign-board, and means at the other side of the body for attaching the body to a sign-board, the last mentioned means comprising a finger having a hooked forward end, and a spring arm pivoted to the body near the forward end of the body, said arm being pivoted to the rear end of the finger, said finger when in clamping position being located between the pivot of the arm and the axis of the body.

13. The combination, with a signboard having a circular opening therethrough, of a socket adapted to engage in said opening and abut against the rear face of the board, hooks carried by the socket and adapted to pass through said opening and engage the front face of the board, and pivoted spring means for operating said hooks, whereby the socket may be clamped to the board in various positions in said opening.

14. A lamp receptacle body, means at one side of the body for engaging a sign-board, and means at the other side of the body for attaching the body to a sign-board, the last mentioned means comprising a clamping member, and a spring arm pivoted to the body near the forward end of the body, the rear portion of said arm being connected to the rear portion of the clamping member.

15. A lamp receptacle body, means at one side of said body for engaging a sign-board, and means at the other side of said body for attaching the body to a sign-board, the last mentioned means comprising a spring arm, said body having an outwardly extending lug near its forward end, said spring arm being pivoted to said lug, and a clamping member extending through said lug, the rear end of said arm being pivoted to the rear end of said member.

16. A lamp receptacle body, means at one side of the body for engaging a sign-board, and means at the other side of the body for attaching the body to a signboard, the last mentioned means comprising a clamping member having a hooked forward end, the rear portion of said clamping member being adapted to swing toward and away from the body, and spring means engaging the rear portion of said member and arranged to draw said member longitudinally into clamping position when said member lies alongside the body.

17. A lamp receptacle having, in combination, a body, an angular clamping member, the forward end of which is adapted to pass

through an opening in the signboard when said clamping member occupies a certain position, means whereby the clamping member is supported for pivotal movement into and out of such position, and means to operate said member.

18. In a lamp receptacle, a body, and means for attaching the body to a sign-board, comprising a finger having a bent forward end, and spring means for drawing said finger rearwardly longitudinally of the body.

19. In a lamp receptacle, a body having a shoulder near its forward end to lie in contact with a signboard and for attaching the body to a signboard, comprising a finger having a bent forward end adapted to lie in front of the signboard, and spring means for drawing said finger rearwardly longitudinally of the body.

20. In a lamp receptacle, a body, and means for attaching the body to a sign-board, comprising a signboard-engaging finger, means whereby said finger is arranged to swing toward and away from the body upon an axis located adjacent to the forward end of said finger, and means for holding said finger against said body.

21. In a lamp receptacle, a body, and means for attaching the body to a sign-board, the last mentioned means comprising a finger having a bent forward end, means whereby said finger is arranged to swing toward and away from the body upon an axis located adjacent to the forward end of the finger, and means to hold said finger against the body and move the finger rearwardly longitudinally of the body.

22. In a lamp receptacle, a body, an angular clamping member, means whereby said member is pivotally movable with relation to the body to dispose the forward end of said member in position to pass through an opening in a signboard, and spring means tending to swing the rear portion of said member against the body and draw said clamping member rearwardly longitudinally of the body.

23. In a lamp receptacle, a body having a shoulder adjacent to its forward end, said shoulder being adapted to abut against the rear side of a signboard, a lug adjacent to said shoulder, said lug having an opening therethrough, a clamping member extending through said opening from a point in front of said shoulder to a point behind the lug, and spring actuating means connected to said lug and to the rear portion of said member.

24. In a lamp receptacle, a body having a shoulder adjacent to its forward end, said shoulder being adapted to abut against the rear side of a signboard, a lug adjacent to said shoulder, said lug having an opening therethrough, a clamping member extend-

ing through said opening from a point in front of said shoulder to a point behind the lug, said member being arranged to swing toward and away from the body upon an axis located adjacent to the forward end of the finger, a spring arm pivoted to said lug and to the rear portion of said member.

In testimony whereof, I hereunto set my hand in the presence of two witnesses.

VICTOR REGINALD DESPARD.

In the presence of—

GEORGE L. CHINDAHL,
MARGARET H. MANN.
